UNITED STATES PATENT OFFICE.

PAUL SPRANGER, OF MARIENFELDE, NEAR BERLIN, GERMANY, ASSIGNOR TO DAIMLER MOTORENGESELLSCHAFT, OF STUTTGART, GERMANY.

CARBURETER.

No. 905,012.

Specification of Letters Patent.

Patented Nov. 24, 1908.

Application filed May 28, 1908. Serial No. 435,533.

To all whom it may concern:

Be it known that I, PAUL SPRANGER, managing director, a subject of the Prince of Reuss, ältere Linie, and resident of 7 Fabrikstrasse, Marienfelde, near Berlin, German Empire, have invented certain new and useful Improvements in Carbureters, of which the following is an exact specification.

This invention relates to carbureters of the type in which the principal air, auxiliary air and mixture outlet openings are simultaneously controlled by means of a single regulating organ which is usually coupled to the governor of the engine.

15 The object of the present invention is to provide means for adapting the operation of such carbureters for use with various kinds of oils and with various temperatures of air.

According to the present invention the 20 regulating organ controlled by the governor reciprocates within a revoluble sleeve carrying the ports of the main air, auxiliary air and mixture whereby adjustment for various oils or various temperatures can be 25 effected by hand through the agency of the revoluble cylinder while the automatic regulation of the action of the carbureter by means of the governor proceeds in the usual way by regulating the position of the reciprocating controlling valve or other organ.

30 Referring now to the accompanying drawings which illustrate this invention in one convenient form Figure 1 is a partial cross section through a carbureter according to the present invention, Fig. 2 is a section on the line A—B Fig. 1, Fig. 3 is a section on the line C—D Fig. 1.

In the drawings oil is introduced by a 35 nozzle *f* while air is introduced into the annular space *a* through a pipe *a'*. The air introduced into the space *a* passes as shown by the arrows in Fig. 3 into the inner annular space *b* and thereby through the main air ports *l* and auxiliary air ports *i* into the central channel of the reciprocating regulating organ *d*. The ports *l* and *i* are carried by a sleeve *h* which surrounds the regulating organ *d*. The regulating organ or valve *d* is

adapted to be moved by a rod *d'* passing through the end wall *r* of the cylinder or sleeve *h*. The rod *d'* is connected to any suitable form of engine governor. The sleeve *h* is provided with a handle *s* by which its position may be adjusted by hand. In addition to the ports *l* and *i* the sleeve *h* is provided with ports *h'* which coöperate with ports *g* in the regulating organ *d*. The ports *i* in the sleeve *h* coöperate with the ports *k* in the regulating organ *d*.

The operation of this device is as follows: Assuming the sleeve *h* to be in the position shown in Fig. 3 then in this case the maximum proportion of auxiliary air is fed in the interior of the regulating member *d* through the ports *k*. If now the handle *s* be moved into the required position the ports *i* will not register exactly with the ports *k* and the auxiliary air will in consequence be throttled. Such a throttling however has no effect whatever on the main air or the mixture outlet ports as the ports *h'* in the sleeve *h* are considerably larger than the ports *g* and therefore permit of the rotation of the regulating member *d* without in any way affecting the opening of the ports *g*. In this way the regulation required for different kinds of oils and for different conditions is simply and efficiently secured.

I claim:

A carbureter having in combination, a 80 casing with air and oil inlets thereto, a hand rotatable sleeve with main air, auxiliary air and mixture outlet ports therein, a reciprocating regulating organ within said sleeve, 85 adapted to control said ports, said reciprocating organ and port carrying sleeve being arranged so that when the port carrying sleeve is rotated only the auxiliary air ports are influenced.

In witness whereof I have hereunto set my hand in the presence of two witnesses.

PAUL SPRANGER.
